UNITED STATES PATENT OFFICE

2,664,006

CIRCULAR KNITTING MACHINE

Erik Frits Lund, Herning, Denmark

Application July 16, 1947, Serial No. 761,174

Claims priority, application Denmark July 28, 1945

2 Claims. (Cl. 66—81)

1

The invention relates to a method for knitting fabrics and apparatuses or looms for the performance of the method.

An essential point of the invention is that the threads for forming the stitches are carried by a row of thread carriers in relation to needles arranged in a row transversally across the fabric being manufactured in such a way that each thread during the crossing gradually forms a series of stitches. The stitches are at once formed in several consecutive series, each series by its individual thread. The columns of stitches may be obliquely to the series.

It is of no importance if the carriers are moved and the needles fixed or the contrary is the case. They may also both be movable in some way or other.

For carrying out the process a row of thread carriers, each carrying its individual thread, advances stepwise or proceeds on the one side of the fabric in relation to a corresponding row of needles on the other side of the fabric. The row of carriers stops after a step in a position opposite the row of needles, each carrier opposite a needle, and stitches are formed simultaneously between each pair or couple of carriers and needles.

After the forming of a stitch the carriers conveying their individual threads advance in some suitable manner one step of desired length from the needles with which they have formed stitches and always in the same direction in relation to the needles and stop opposite other needles in the row, where new stitches are formed.

This method is especially suitable for circular knitting.

In circular-knitting machines the thread-carriers are assembled in a circular system like the needles. The two circular systems are co-axial. There are as a rule the same number of thread-carriers and needles. The whole needle system is moved up and down together while the thread-carriers lead the threads towards and away from the needle system in time with the up-and-down motion of the needles as both systems are controlled by the same member. During these movements stitches may be formed in per se known manners. After the forming of a series of stitches a movement is imparted to the thread-carriers system or the needle system, for instance, to the extent of the width of a stitch at a time.

By means of the process described above an especially rapid knitting is achieved, as a long row of needles, possibly the total number of needles in one row of needles, will knit stitches

2

simultaneously. Consequently it is possible to attain a production of fabric just as quickly as by the production of soft knitted and Raschel fabrics.

5 In the completed fabric each thread, or part of thread, forms its row of stitches transverse to the longitudinal or advancing direction of the fabric. It is, consequently, possible to produce cross-striped fabrics.

The process according to the invention and apparatuses according to the invention will be further explained below with reference to schematic drawings illustrating a form of production for a fabric according to the invention and various embodiments of the apparatus according to the invention.

Fig. 1 is a view in elevation of, partly in section, of a circular knitting machine embodying the invention.

Figs. 2 and 3 are enlarged views showing details of the machine illustrated in Fig. 1.

Fig. 4 is an enlarged view of a portion of Fig. 1.

Referring to Fig. 1, an embodiment of the invention is illustrated as applied to a circular knitting machine, a portion of which is shown on a larger scale in Fig. 4.

The machine of Fig. 1 comprises a revolute vertical needle cylinder 101 having vertically extending needle guiding grooves 102 formed on the periphery thereof in the usual manner, being arranged to receive tongue- or latch-needles 103 forming a series of needles and a horizontal, circular groove housing a spring 105 for keeping the needles in their place. The feet 106 of the needles enter into a recess 107 in a vertically reciprocating guide ring 108. A face 109 on the upper part of the ring bears against a corresponding face 110 on thread-carriers 111 each adapted to swing on a circular axle 112 the number of which as a rule equals the number of needles. The carriers are placed around the needle cylinder. By means of a circular spring 119 the thread-carriers are pressed towards the needle cylinder. Through an eye 113 on the thread-carriers endless threads 127 are carried from spools or rollers 128. On the way between the spools 128 and the carriers the threads pass a thread controller 129 in the usual manner. The guide ring 108 which, as it will appear from the above, controls the vertical movements of both needle system and thread-carrier system in any desired, suitable manner, and is itself operated by means of some bars 114 the lower end of each of which projects into a corrugated path 115 in a ring 116. The bars may be supported against

the surfaces of the path by means of roller bearings or the like 117 and 118. The rings 116 and 108 rotate one in relation to the other.

The machine may e. g. be mounted and driven in the following manner:

The needle cylinder 101 with its accessories may be mounted in a frame 130. A motor 131 supplies the necessary force. Through a gear 132 this motor rotates the shaft 133, on which a pinion 134 is fixed. This pinion is in mesh with a gear wheel 135 fixed on the ring 116, which latter is rotated continuously during the work. The needle cylinder 101 is rotated stepwise by means of two eccentric discs 136, 137 fastened on the shaft 133. One of these discs 137 moves a bar 138, Fig. 3, which is slidingly journaled in a bearing 139 fixed on the frame 130 in some suitable manner. The bar has at its one end a wheel 140 which by means of a spiral spring 141 is pressed against the disc 137. At its other end the bar has a pawl 142 which is pressed against a toothed ring 143 on the needle-cylinder by means of a spiral spring 144. This pawl serves for moving the needle cylinder in anti-clockwise direction.

The other disc 136 serves to stop this movement of the needle-cylinder intermittently by means of a bar 145 having pivots 146 journaled in bearings (not shown). Bar 145 is journaled to revolve in a clockwise and anti-clockwise direction, and is not permitted to slide longitudinally.

At one end the bar has a wheel 147, which by means of a spiral spring 148 is pressed against the said disc 136. At the other end the bar 145 has a pawl 149 which can engage the teeth of a toothed ring 150 on the needle cylinder.

When the two eccentric discs 136 and 137 are adjusted in a suitable manner in relation to each other it is obvious that the disc 137 will push the needle cylinder a step forwards and that the disc 136 afterwards will suddenly stop this movement.

The circular axle 112 is stationarily mounted on some part of the frame 130.

The fabric passes from the needle row down through the center of the hollow needle cylinder and is rolled up on a drum 151 journaled in bearings 152 slideably fixed to the needle cylinder 101. The drum carries two wheels 153 running on a circular rail 154. Adjustable spiral springs 155 press the wheels against the rail. According to the strain in the fabric and the springs the wheels are pressed more or less against the rail and the drum will rotate more or less rapidly. In this way the rolling up of the fabric can be regulated in such a way that it will follow the production of the fabric.

It will be understood that the way in which the needle cylinder and its accessories are mounted in the frame, as well as their operation form no part of the invention. These parts of the machinery are only mentioned as an example and they can be designed in several other manners.

The knitting process is performed as follows:

By means of the vertically reciprocating guide ring 108 the needles are carried upwards un-

til they reach a height where the catches of the needles are clear of the newly formed stitches. During this movement the thread-carriers recede and as the needle thereafter is moved downwards

5 the pawl 142 drives the needle cylinder system forwardly to the extent of the width of one stitch. Thereafter the thread-carriers are moved towards the needles whereby a thread from one needle in the row is laid into the next succeeding 10 needle, and so on the whole way round. The insertion of the thread must occur before the catch of the needle is closed after the stitch just performed, so as to place the thread in the eye of the needle, and by the casting-off a new stitch 15 is completed.

I claim:

1. A circular knitting machine having a needle cylinder, a circular series of needles carried by said needle cylinder, said needles having foot portions, pivotally mounted thread carriers arranged in a circular series concentric with said needle cylinder and surrounding said series of needles, one carrier for each needle, a travelling guide ring which reciprocates in a direction parallel to 20 the axis of said cylinder, said guide ring being provided with a recess in which said foot portions of said needles are adapted to enter in order that they may be simultaneously actuated for reciprocation therewith and comprising a face 25 which bears against corresponding faces on said thread carriers, the thread carrying parts of said carriers being actuated to move away from said needles by the movement of said guide ring in one direction, and means for pressing said thread carrying parts of said carriers toward said needles during movement of said guide ring in the opposite direction to form stitches, said series of 30 needles and carriers rotating stepwise always in the same direction in relation to each other.

2. A circular knitting machine as defined in claim 1, wherein said machine includes a further ring provided with a corrugated groove therein, and in which said guide ring is provided with members which project into said corrugated groove, said further ring and said guide ring being adapted to rotate one in relation to the other.

ERIK FRITS LUND.
